REVERSIBLE TIE

Frederick J. Benson, North Sacramento, Calif.

Application April 19, 1943, Serial No. 483,689

1 Claim. (Cl. 2—146)

The present invention relates to improvements in a reversible tie, and it consists of the combinations, constructions and arrangements hereinafter described and claimed.

An object of my invention is to provide a reversible tie that can be manufactured in the same length of time as the usual four-in-hand tie and that has one design or material on one side of the tie and a different design or material on the other side. The tie can function as two distinct ties.

A further object of my invention is to provide a device of the type described which can be machine stitched rather than hand stitched, thus saving time in the manufacture of the tie.

Still a further object of my invention is to provide a tie which has novel means to prevent it from becoming wrinkled after frequent tying.

Other objects and advantages will appear in the following specification and the novel features will be particularly pointed out in the appended claim.

My invention is illustrated in the accompanying drawing forming a part of the application in which

Figure 1 is a plan view of the large end of the tie showing the two pieces of material turned inside out to expose the lining;

Figure 2 is a transverse section taken along the line 2—2 of Figure 1;

Figure 3 is a plan view of the small end of the tie showing the two pieces of material turned inside out for stitching;

Figure 4 is a transverse section taken along the line 4—4 of Figure 3;

Figure 5 is a longitudinal section through the large end of the tie after this end has been turned right side out and is temporarily covered by the small tie end that still remains turned inside out, but is stitched to the neck portion of the large tie end;

Figure 6 is a longitudinal section similar to Figure 5; and

Figure 7 is a plan view of the completed tie.

While I have shown only the preferred form of my invention, it should be understood that various changes or modifications may be made within the scope of the appended claim without departing from the spirit of the invention.

In carrying out my invention, I provide a tie formed of two sections, the larger section being designated generally by A, see Figure 1, and the smaller section being designated generally by B, see Figure 3. Section A has two tie-shaped pieces of cloth 1 and 2, see Figure 2, stitched together

along their side edges at 3 and 4. The pieces 1 and 2 are preferably of different materials or designs and are about two feet long with their outer surfaces facing each other. Strips, 5 and 6, of muslin about nineteen inches in length extend from the narrow ends 7 of the pieces and parallel the sides. A lining section 8, of slightly less length than the strips and slightly narrower than the pieces is secured to the strips by stitching 9 and 10, see Figure 2. The stitching 3 and 4 secures the strips to the pieces. The narrow end of the lining 8 is cut along a bias as at 11.

Transverse ribs or tucks 12 are formed in the lining to increase its resiliency so that the lining 13 will spring back into shape when the tie knot is untied and will aid in returning the pieces 1 and 2 to normal position. A second lining section 13 about nineteen inches long, has its smaller end 14 cut on a bias and lapped for a short distance with the lining section 8. The stitching 3 and 4 secures the end of the lining section 13 to the lining section 8 as shown in Figure 1. Tucks 15 are also formed in the second lining section 13 to increase its resiliency. The parts of the larger section A assume the position shown in Figures 1 and 2 while they are machine stitched together at 3, 4, 9 and 10. After this is done, the smaller section B is made before the pieces 1 and 2 are turned inside out.

In Figures 3 and 4, I show the smaller section B. Pieces 16 and 17 about two feet long and of the shape shown are placed with their outer surfaces together and machine stitched along their edges at 18 and 19. The piece 16 is of the same material or design as the piece 1. The two sections A and B are now joined together. First the section A is turned right side out so as to inclose the strips 5 and 6 and the lining 8. The machine stitching 3 and 4 is hidden by the turning right side out of the section and so is likewise the stitching 9 and 10. The strips 5 and 8 are stitched to the lining section before the strips are stitched to the pieces 1 and 2. When the section A is turned right side out, the lining section 13 will still project beyond the narrow edge of the section as shown in Figure 5. The smaller section B while still turned inside out is telescoped over the larger section A so that the narrow edge 20 of the section B is aligned with the edge 7 of the section A. A transverse line of machine stitching 21 now secures the two sections together adjacent their narrow edges 7 and 20.

The next step is to turn the section B right side out by grasping the large end 22 and turning

both pieces 16 and 17 back on themselves so that this "skinning" movement will uncover the section A and cover the lining section 13 as illustrated in Figure 6. The transverse stitching 24 is now covered and both sections A and B are turned right side out. The stitchings 16 and 19 are also covered by this turning of the section B right side out. The edges 22 of the section B are turned in and stitched as at 23 while the outer edges 26 of the section A are turned in and stitched as at 25, if desired.

The completed tie is illustrated in Figure 7 with the section A being connected to the section E. Machine stitching 26 and 27 paralleling the edges of the narrow portion of the section B is also indicated in Figure 7 to secure the lining section 13 to the pieces 16 and 17. This prevents the section B from remaining wrinkled when the knot is untied.

From the foregoing description of the various parts of the device, the operation thereof may be readily understood. The tie may be tied with the usual four-in-hand knot. One side of the tie is of one material or design while the other side is of a different material or design. The reversible tie gives the wearer a two tie advantage since either side of the tie can be worn outermost. The tie will not wrinkle due to the muslin strips,

the transverse ribs or tucks in the lining sections and the stitching at 26 and 27. The device is simple in construction and can be machine stitched throughout.

5 I claim:

The herein described method of making a machine-stitched reversible tie which comprises: placing the right sides of two half-length tie-shaped pieces of different cloth face to face and stitching them along their edges to form one tie section, stitching muslin strips to the sides of the tie section after a lining section has been stitched to the strips, stitching an end of a second lining section to the ends of the strips, turning the tie section inside out so that the two cloth pieces enclose the strips and first-mentioned lining section; placing the right sides of two other half-length tie-shaped pieces of the same two kinds of material face to face and stitching them along their edges to form a second tie section, telescoping the second tie section over the first tie section, stitching the narrow ends of the two tie sections together, and in pulling the second tie section off from the first tie section and over the second lining section to form the completed tie.

FREDERICK J. BENSON.
